CLAIM

The ornamental design for a vehicle warning light, substantially as shown and described.

DESCRIPTION

FIG. 1 is a top isometric view of a vehicle warning light, shown in a bezel.

FIG. 2 is a left-side elevation view thereof, of which a right-side elevation view is a mirror image.

FIG. 3 is a front elevation view thereof.

FIG. 4 is a rear elevation view thereof; and,

FIG. 5 is a top plan view thereof.

In the figures, the broken lines are illustrative of portions of the vehicle warning light and environment forming no part of the claimed design.
